ATTORNEYS

UNITED STATES PATENT OFFICE

WILLIAM BEST, OF CHICAGO, ILLINOIS

KEY REEL

Application filed October 29, 1928. Serial No. 315,885.

My invention relates to improvements in key reels, and it consists in the combinations, constructions, and arrangements herein described and claimed.

5 An object of my invention is to provide an improved device over that set forth in my prior Patents No. 1,485,663 of March 4, 1924, and No. 1,567,783 of December 29, 1925. These improvements lie primarily in 10 a construction whereby when the cord to which the key ring and keys are secured is retracted, means is provided for positively and automatically locking the cord so that the keys will be firmly supported.

15 A further object is to provide a device in which the construction is such that the weight and size of the device are reduced to a minimum.

20 A further object is to provide a device in which the parts may be readily secured together, thereby facilitating the assembly of the device.

25 Other objects and advantages will appear in the following specification, and the novel features of the invention will be particularly pointed out in the appended claims.

My invention is illustrated in the accompanying drawings, forming part of this application, in which

30 Figure 1 is a face view of my device attached to a belt,

Figure 2 is an elevation of a portion of my device,

Figure 3 is a sectional view taken along 35 the line 3—3 of Figure 1,

Figure 4 is a detail fragmentary view, and

Figure 5 is a detail view of a portion of my device.

In carrying out my invention, I provide

40 a saucer-shaped circular member 1 formed preferably from suitable sheet metal. A thin circular disc 2 is secured to the member 1 as shown in Figure 1. The saucer-shaped member 1 is provided with a depressed portion 3, the latter being formed eccentrically with respect to the transverse axis of the saucer-shaped member 1.

45 A disc-like member 4 having an extended portion 5 is provided. Referring to Figure 3, it will be noted that the disc 2 is formed

with a bearing portion 6 for supporting the disc-like member 4. A companion disc member 7 is mounted upon the extended portion 5, as shown in Figure 3. The extended portion 5 is originally tapered slightly and is expanded after the companion disc 7 is disposed upon the extension. Thus it will be seen that the companion disc 7 is securely mounted upon the extended portion.

55 The companion disc 7 is spaced from the disc member 4 to provide a guideway for a pull cord 8. One end of the pull cord 8 is wound around the extended portion 5 and passes through an opening 9 in the companion disc 7, see Figure 2. A rivet or screw 10 passes through the device, as shown in Figure 3. The rivet 10 is concentrically disposed with respect to the eccentrically formed portion 3. A sleeve 11 is mounted upon the rivet and between the disc 2 and the saucer-shaped member 1. The sleeve 11 is provided with a slit 12, see Figure 5.

60 A spiral spring 13 is disposed within the extended portion 5, as shown in Figure 2. One end of the spring 13 is secured within the slit 12 of the sleeve 11 and the other end is secured with respect to the extended portion 5 by means of a projection 14 which is formed integral with the extended portion. The sleeve 11 is provided with projections 15 which extend through the disc member 2 so that the sleeve 11 is held against rotation. The spring 13 is not shown in Figure 3 for the sake of clearness.

65 The pull cord 8 is provided with a terminal 16 having a hook member 17 for receiving a key ring 18 upon which a key or a number of keys 19 may be disposed. The terminal 16 is tapered and is adapted to enter an opening O in the casing A comprising the saucer-shaped member 1 and the disc member 2. The opening O is enlarged at 20 and constricted at 21, see Figure 4.

70 When it is desired to employ the key, the latter is grasped and pulled away from the casing A. As the pull cord 8 is moved outwardly, the disc member 4 and the companion disc 7 rotate upon the bearing portion 6.

Such rotation will of course increase the tension of the spring 13. On the release of the key, the tension of the spring 13 will cause a counter-rotation of the guideway for the pull cord 8 until the key ring 18 is disposed in its normal position, as shown in Figure 1. At this time the terminal 16 will be firmly locked by reason of the enlarged end of the terminal bearing against the constricted portion of the opening O. The constricted portion 21 receives the hook 17, as shown in Figure 1, so that the projection of the hook from the casing A is reduced to a minimum.

15 A suitable clip 22 is secured to the disc member 2 by means of the rivet 10. The clip is mounted for rotation so that the casing A may be disposed in any desired position. Any suitable means may be provided for locking the clip against rotation such as projections formed in the disc member 2.

20 The portion 3 is formed eccentrically so that space is provided for the terminal 16 between the outer edges of the members 4 and 7 and the edge of the casing A. Thus it will be seen that the ultimate diameter of the casing A is reduced to a minimum.

I claim:

25 1. A key reel comprising a casing having a depressed portion formed eccentrically with respect to the transverse axis of the casing, said depressed portion being arranged to provide a terminal chamber within the casing, a cord-holding device disposed within the casing and arranged concentrically with respect to the depressed portion, spring means for actuating the cord-holding means, and a cord wound around said cord-holding means and provided with a terminal upon one end, said casing being provided with an opening having a constricted portion and communicating with said terminal chamber, said terminal being arranged to enter the opening in the casing and to be held therein by the constricted portion of said opening.

30 2. A key reel comprising a casing having a depressed portion formed eccentrically with respect to the transverse axis of the casing, said depressed portion being arranged to provide a terminal chamber within the casing, a cord-holding device disposed within the casing and arranged concentrically with respect to the depressed portion, spring means for actuating the cord-holding means, a cord wound around said cord-holding means and provided with a terminal upon one end, said casing being provided with an opening having a constricted portion and communicating with said terminal chamber, said terminal being arranged to enter the opening in the casing and to be held therein by the constricted portion of

said opening, and means associated with said terminal for supporting a key.

3. A key reel comprising a casing having a depressed portion formed eccentrically with respect to the transverse axis of the casing, said depressed portion being arranged to provide a terminal chamber within the casing, a cord-holding device disposed within the casing and arranged concentrically with respect to the depressed portion, 70 spring means for actuating the cord-holding means, a cord wound around said cord-holding means and provided with a terminal upon one end, said casing being provided with an opening having a constricted portion and communicating with said terminal chamber, said terminal being arranged to enter the opening in the casing and to be held therein by the constricted portion of said opening, means associated with said terminal for supporting a key, and means associated with the casing for removably securing the casing upon a belt.

4. A key reel comprising a casing having an eccentrically arranged depressed portion for forming a terminal chamber within the casing, said casing being provided with an opening having a constricted portion and communicating with the terminal chamber, a cord-holding device disposed within the casing and arranged concentrically with respect to the eccentrically arranged depressed portion, and a cord associated with said cord-holding device and being provided with a terminal adapted to enter the opening in said casing and to be held therein by the constricted portion of said opening.

5. A key reel comprising a casing having an opening therein, a spring-actuated drum disposed within the casing, a cord wound about the drum and passing through said opening, and a key-holding device secured to the end of the cord projecting through said opening and being provided with means arranged to pass through the opening for engaging the edge of the same, whereby said key-holding device is positively held against outward movement.

Signed at Chicago, in the County of Cook, and State of Illinois this 12th day of October, A. D. 1928.

WILLIAM BEST.
